COMBINATION DOORCHECK AND DISPLAY

James W. Wyatt and John H. Pollard, Dallas, Tex., assignors to Screen Advertising, Incorporated, Dallas, Tex., a corporation of Texas

Application July 12, 1934, Serial No. 734,762

7 Claims. (Cl. 40—60)

This invention relates to new and useful improvements in combination door checks and displays.

One object of the invention is to provide an improved combination door check and display, the latter preferably being a sign carrying indicia, advertising matter, symbols, or the like.

An important object of the invention is to incorporate in an ordinary door check, a display device which is positioned in view of persons passing through the door to which the check is applied, said display device being arranged to be swung each time the door is opened.

Another object of the invention is to incorporate in an ordinary swinging door check, a display device which is preferably a sign and which is so arranged as to be capable of a limited swinging movement independently of the swing of the door check, whereby the reverse side of the sign is exposed when the door is opened.

A further object of the invention is to incorporate in an ordinary swinging door check, a display device which is arranged to be swung each time the door check is operated, whereby the attention of an observer is attracted to the indicia or advertising matter displayed on the device.

Still another object of the invention is to provide an improved door check and display device, wherein the device is incorporated in the check, in such a way that it is unnecessary to change the general structure of said check, it being only necessary to add one moving part on which said device is mounted.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is an elevation of a door having the combined door check and sign, constructed in accordance with the invention, applied thereto, said door being in a closed position.

Figure 2 is a similar view, showing the door in an open position.

Figure 3 is a horizontal cross sectional view, taken on line 3—3 of Figure 1.

Figure 4 is a view similar to Figure 3 and showing the check swung to its outer position, and

Figure 5 is a vertical sectional view, taken on line 5—5 of Figure 4.

In the drawing, the numeral 10 designates the frame of a door and 11 the door proper. On the

frame, I mount a door check 12 including the usual supporting bracket 13 which is fastened to the door frame by suitable wood screws 14. A swinging member 15 comprising a pair of arcuate bars 16, disposed one above the other and secured together by a vertical tie pin 17, is pivotally mounted between the arms of the bracket on rivets 18. As shown in Figure 3, the member is pivoted off center nearer the inner end of said member.

A roller 19 is mounted between the bars 16 at their extreme inner ends, and a larger roller 20 is secured between said bars at the outer ends thereof. The rollers may be constructed of any suitable material but are preferably composed of rubber, rubber compound, or other shock absorbing material. When the door 11 is in a closed position (Figure 3) the roller 20 is arranged to engage the stile of said door, as will be hereinafter explained.

A vertical crank shaft 21 is mounted to swing between the bars 16 at a point between the rivets 18 and the outer ends of said bars. A coiled spring 22 has one end secured to the offset portion of the crank shaft, and the other end fastened to an ear 23 on the rear of the bracket 12. This spring is constantly under pressure.

In Figure 3, the roller 20 on the outer end of the member 15 is engaging the door stile and the spring 22 is exerting its pressure to hold said door closed. It is pointed out that said spring is off center of the pivot point of the member 15 and therefore its tension is holding the roller 20 against the door. The spring has also swung the crank shaft 21 to the position shown in Figure 3. When the door is opened, the roller 20 riding on the door stile, causes the member 15 to be swung. As the member swings the outer end of the spring 22 and the crank shaft to which it is fastened are also swung. As soon as the spring 22 passes the pivot point of the member 15, it immediately exerts its pressure to pull the member 15 to its outer position, as shown in Figure 4. At the same time the crank shaft has been rotated to an off center position on the opposite side of its pivot and the spring also holds the crank shaft in this off center position. (Figure 4.)

It is pointed out that the distance from the rivets 18 to the roller 20 is much greater than the distance between said rivets and roller 19. This causes the roller 20 to travel in a larger arc than the roller 19 when the member is swung by the door. This variation in the arcs through which the rollers travel cause the roller 20 to swing out of the path of the door when the door is

opened. (Figure 4.) Since the roller 19 describes a smaller arc, it swings in behind the door as said door opens and is, therefore, in the path of said door when the same is closed. The closing of 5 the door causes the engagement of the back of said door with the roller 19, thereby swinging the member 15 back to the position shown in Figure 3. The return swing of the members swings the crank shaft 21 and spring 22 to its 10 first position, said spring holding the door closed. Thus, it will be seen that the spring 22 holds the member in its two positions. The door merely swings the member to an off-center position, the spring tension completing the swing of said member. 15 Due to the mounting of the crank shaft, said shaft is swung each time the member is operated.

The parts, thus far described, with the exception of the crank-shaft 21 are of the usual construction and are subject to variation. As has been described, the shaft 21 is arranged to swing and a display device or exhibitor 25 is fastened to the shaft and is arranged to be swung therewith, whereby each time the member 15 is swung 25 the sign is swung to display its reverse side. Thus, with the door closed, the front side of the device is displayed (Figure 1) and when the door is open, the reverse side is visible.

The sign includes a frame 26 having a display 30 panel 27, carrying suitable indicia, mounted therein. The frame is provided with a pair of horizontally extending arms 28 which have their ends fastened to the upper and lower ends of the crank shaft 21 above and below the offset 35 in said shaft. If desired, the arms 28 may be made integral with the crank shaft but this is not essential.

The arms 28 are secured in a position so that 40 when the door check 12 is holding the door closed the sign is substantially parallel with the face of the door and is clearly visible to one entering the door. When the door is opened and the member 15 of the check is swung to the position shown in Figure 4, the sign, being secured to the crank shaft 21 is swung with said crank shaft and the weight of the swinging sign, together with the tension of the spring 22 on the shaft 21, pulls 45 said sign around so that its reverse or opposite side is visible. The sign strikes the tie pin 17 of the member 15 to limit the swing in this direction, whereby the sign is stopped in a position substantially parallel to the face of the door, thereby clearly displaying its reverse side (Figure 2).

55 When the door is closed and the member 15 is returned to the position shown in Figure 3, the sign is again swung to its first position (Figure 3) due to the action of the crank shaft 21 and the spring 22. The movement of the sign is limited 60 in this direction by the sign striking the curved edge of the bars 16. It is pointed out that the weight of the sign as it swings around aids in rotating the crank arm to swing it to its off center position, whereby a more positive action is assured.

65 The construction of the sign is immaterial as it may be a solid panel without the frame 26 and having the arms 28 made integral therewith. Also, it would be possible to make the panel removable from the frame, whereby the sign or display could be readily changed.

70 It is pointed out that the sign is at all times in a position substantially parallel to the face of the door, where it is clearly visible to the persons entering the door. Suitable advertising indicia

may be displayed on the sign and a valuable advertising space is utilized. Further, both sides of the sign carry indicia, and regardless of whether the door is opened or closed, the sign is always in full view of the observer.

5 The description which has been given recites more or less detail of a particular embodiment of the invention, which is set forth as new and useful; however, we desire it understood that the invention is not limited to such exact details of 10 construction, because it is manifest that changes and modifications may be made, within the scope of the appended claims, without departing from the spirit of the invention.

15 What we claim and desire to secure by Letters Patent, is:

1. A door check and display device for a swinging door comprising, a swinging member arranged to be swung by the opening and closing of the door, a display having a swinging mounting on 20 said member so as to expose opposite sides each time said member is swung by the door, and means for swinging the display independently of and concurrently with the member when the member is swung by the opening or closing of the 25 door.

2. A door check and display device for a swinging door comprising, a swinging member arranged to be swung by the opening and closing of the door, a display having a swinging mounting on 30 said member so as to expose opposite sides each time said member is swung by the door, means for swinging the display independently of and concurrently with the member when the member is swung by the opening or closing of the 35 door, and means for limiting the movement of the display.

3. A door check and display device for a swinging door comprising, a swing member located to be 40 engaged and arranged to be swung by the opening and closing of said door, a crank shaft mounted on the member and arranged to swing independently of the member, means for swinging the crank shaft on its mounting when the swinging member is swung, and a display secured to the crank shaft, whereby the swinging 45 of the member will swing the shaft and display.

4. A door check and display device for a swinging door comprising, a swinging member located to be engaged and arranged to be swung by the 50 opening and closing of said door, a crank shaft mounted on the swinging member and arranged to swing independently when the member is swung, means for swinging the crank shaft on its mounting when the swinging member is 55 swung, a display carried by the crank shaft, and means for limiting the swing of the crank shaft and member, whereby the movement of the display is limited.

5. A door check and display device for a swinging door comprising, a swinging member including a pair of pivoted arcuate arms secured together, said arms being arranged to be engaged by the door to swing the member, a crank shaft mounted to swing between the arms, means for swinging the crank shaft on its mounting between the arms when the member is swung and a display panel carried by the crankshaft and arranged to swing when the member is swung and to further swing independently of the member 70 on the crank shaft.

6. A door check and display device for a swinging door comprising, a swinging member including a pair of pivoted arcuate arms secured together, said arms being arranged to be engaged 75

by the door to swing the member, a crank shaft mounted to swing between the arms, means for swinging the crank shaft on its mounting between the arms when the member is swung, a display panel carried by the crankshaft and arranged to swing when the member is swung and to further swing independently of the member on the crank shaft and means for limiting the movement of the panel to stop it in a position substantially parallel with the door face.

7. A door check and display device for a swinging door comprising, a bracket, a member pivoted to said bracket and including a pair of

pivoted arcuate arms secured together, said arms being arranged to be engaged by the door to swing the member, a crank shaft mounted to swing between the arms, a spring fastened between the shaft and the bracket and exerting its pressure on said shaft and member when the same are off center, and a display panel carried by the crankshaft and arranged to swing when the member is swung and to further swing independently of the member on the crank shaft.
